APPARATUS FOR CUTTING QUARTZ OSCILLATOR BLANKS

William C. Speed, New York, N. Y., assignor to
Reeves-Ely Laboratories, Inc., New York, N. Y.,
a corporation of New York

Application November 20, 1943, Serial No. 511,204

11 Claims. (Cl. 125—14)

1

This invention relates to quartz oscillator plates and has for its object certain improvements in apparatus for sawing blanks from quartz crystals.

A variety of types of sawing machines and sawing techniques have been proposed for the making of oscillator plates. In all cases a device is used to hold the quartz crystal in proper orientation for sawing. The crystal is oriented and then mounted so it can be fed to the saw or the saw brought to the crystal. The crystal is, for example, solidly imbedded in plaster of Paris or otherwise cemented to a base made of plywood, glass, etc. The base is then clamped to the cutting table. A natural face, or a trued surface, of the crystal is usually used as a base for the mounting; the face or surface being, for example, aligned with the surface of the cutting table. The table is then turned to bring the crystal in the desired angle of cut with respect to the saw.

This practice has a number of serious disadvantages. It is difficult to align the crystal accurately unless it has a natural face of sufficient size. Crystal with such natural faces are now the exception rather than the rule. This is one of the reasons why the crystals are given preliminary cuts to obtain a trued section with a flat surface that can be used to position the crystal on the cutting table. Special steps must, therefore, be taken to obtain trued sections, and there are nevertheless opportunities for error in mounting and aligning the crystal to the saw. These difficulties are, of course, greatly increased when working with raw crystals that do not have any, or ample, natural faces.

I have discovered that these disadvantages may be substantially overcome. The quartz crystal may be readily and accurately cut into oscillator plates. It may be mounted and aligned with respect to its axes and may be cut or sawed without disturbing the alignment. As a result of these improvements, substantial economies may be effected over the practice heretofore followed and oscillator plates of predetermined angle of cut may be regularly obtained.

In accordance with the method of invention, the optical and electrical axes of a quartz crystal, or section of crystal, are placed in predetermined relationship with a given reference line removed from the crystal. The crystal is then cut at a predetermined angle of cut with respect to the reference line while maintaining the optical and electrical axes of the crystal fixed in their relationship to the reference line.

The apparatus comprises a cutting machine, an adjustable guide support, a removable quartz

2

holder adapted to engage the guide support in a predetermined position, means associated with the holder for maintaining the optical and electrical axes of a quartz crystal mounted thereon in predetermined fixed relationship to a reference part of the holder, means for placing the guide support and hence the holder and crystal at a predetermined angle of cut with respect to the cutter, and means for advancing the guide support, holder and crystal as a unit to the cutter at such predetermined angle of cut while maintaining the optical and electrical axes of the crystal fixed in their predetermined relationship to the reference part of the holder.

15 The invention will be better understood by referring to the accompanying drawings, taken in conjunction with the following description, in which:

Fig. 1 is a side elevation, partly in section, of 20 an apparatus illustrative of, and adapted for, a practice of the invention;

Fig. 2 is a plan view of the same apparatus;

Fig. 3 is an enlarged side view of a portion of 25 the apparatus, partly in section; and

Fig. 4 is an enlarged plan view of a portion of the apparatus.

The apparatus shown comprises a sawing machine 10, a quartz crystal holder 11, an adjustable guide support 12, an upper carriage 13, and a lower carriage 14, all of which are suitably mounted on a base 15, which is in turn supported by a framework, not shown, to place the carriages and holder at a convenient level for the operators of the apparatus.

35 Referring to Fig. 1, the apparatus shown includes a circular saw 16, mounted on a shaft 17 extending through the free end of a pull-down arm 18. The pull-down arm is pivotally secured to a shaft 19 near its other end, the shaft being 40 rotatably supported by a pair of spaced vertical supports 20. The rear end of the pull-down arm is provided with an adjustable counterweight 21. An upright arm 22 is supported on a cross-arm extending across the vertical supports. The pull-down arm is movably interconnected to the upright arm by means of a pneumatic shock absorber 23 of conventional construction. When the saw is pulled downwardly, by pulling down the pull-arm, the casing of the shock absorber also moves downwardly away from a stationary piston (not shown) secured to the upper end of the upright arm. Air then rushes into the space between the piston head and the lower part of the casing. When the saw is released, the counterweight forces it upwardly into an inoperative

45

position. The upward action of the pull-down arm is retarded when the casing of the shock absorber rises around the piston, by permitting the air in the casing to exit therefrom in regulated amounts.

Shaft 19 is provided with a pulley 24 which is in turn fitted with a drive belt 25 connecting a source of power, not shown. Shaft 19 is also provided with a pulley 26 and shaft 17 with a pulley 27. A drive belt 28 connects the two pulleys so that rotating power may be transmitted to the saw.

The particular quartz crystal holder shown is more fully described and claimed in my copending application Serial No. 511,198, filed November 20, 1943. It comprises a series of superposed supports or bases: a fixed base A, a lower tiltable base B, an upper tiltable base C and a rotatable base D. Bases D and C are pivotally tiltable at right angles to each other as well as toward and away from base A. Base D is rotatable laterally on base C. A quartz crystal 30 is shown mounted on base D.

Base A is provided with an inverted guide channel 31 open at both ends, rectangular in cross-section, and adapted to fit over guide support 12, also rectangular in cross-section. The part of the holder that defines the channel is advantageously used as a reference part to which the optical axis and an electrical axis of the crystal may be suitably adjusted. A pair of spaced pivot posts 32 and 33 is integrally secured to and centrally of the base at opposite ends; the upper ends of the posts being rounded, as shown, so that base B may be supported and readily tilted thereon. A pair of spaced bolts 34 and 35 is integrally secured to base A at diagonal corners, the bolts being sufficiently long to extend through and a convenient distance above base B.

Base B is provided on its underside with a spaced pair of concave recesses which are adapted to receive and to accommodate the rounded upper ends of pivot posts 32 and 33 respectively extending above base A. The opposite sides of base B have cut-away portions to provide free working space above bolt slots 44 and 45 respectively in base A. Base B is also provided with a pair of slotted bolt holes, not shown, at diagonal corners to accommodate bolts 34 and 35, with nuts 46 and 47, respectively in base A. A pair of spaced pivot posts 48 and 49 is integrally secured to and centrally of the base at opposite sides, the upper ends of the posts being rounded, as shown, so that base C may be supported and tilted thereon. These pivot posts are aligned at right angles to pivot posts 32 and 33 of base A. A pair of spaced bolts 50 and 51 is integrally secured to base B at diagonal corners, the bolts being sufficiently long to extend through and a convenient distance above base C.

Base C is provided on its underside with a pair of spaced concave recesses which are adapted to receive and accommodate the rounded upper ends of pivot posts 48 and 49 extending above base B. The diagonal corners are cut away, as shown, to permit ready access to bolts 34 and 35 extending above base B. Base C is also provided with a pair of slotted bolt holes, not shown, at the other diagonal corners to accommodate bolts 50 and 51 with nuts 64 and 65, respectively, in base B. The upper side of base C is provided with a circular recess 66 adapted to receive and accommodate the lower portion of base D. A spaced pair of threaded bolt holes, not shown,

extend through base C at opposite sides, and accommodate bolts 67 and 68.

Base D consists of a circular bottom disk 80, preferably of metal, integrally secured to a smaller circular top disk 81, preferably made of fiberboard or the like. An outer annular clamping shoulder 82 is provided by the bottom disk due to the smaller diameter of the top disk. A pair of clamps 83 and 84 is attachable to base C by bolts 67 and 68, respectively in base C. Each clamp has a zig-zag configuration, the outer end being provided with a narrow depending shoulder portion adapted to rest on the top of base C and to pivot thereon. The other end of the clamp consists of a laterally extending portion adapted to be pressed downwardly on the top of base D when bolts 67 and 68 are tightened.

Guide support 12 is in turn secured to a base 90 located at the bottom of tray 91 which is adapted to catch cutting liquid used on the saw when cutting quartz crystals. Base 90 is provided with a pair of bolts 92 and 93 extending through the guide support and slots 44 and 45 in base A so that it and the lower fixed base A of the holder may be suitably secured to one another. The base and tray are in turn rotatably secured to an outer hollow shaft 94, the lower end of which rests slidably on a stationary collar 95. An inner solid shaft 96 is secured to the upper side of the collar and extends upwardly within the hollow shaft. The construction is such that the outer shaft and hence the tray, guide support, and the holder may be swiveled around the inner shaft. A set screw 97 extends through the wall of the outer shaft so that the two shafts may be locked in any desired position. The outer surface of the outer shaft is provided with a suitable scale 100 so that the guide support and hence the holder and crystal may be swiveled a predetermined amount with respect to the line of cut of the saw. The movable parts may then be locked in their adjusted position by the set screw.

Collar 95 is in turn secured to a table 101 on upper carriage 13 which is slidably interlocked with a table 102 on lower carriage 14. The two tables are adapted to slide relatively to one another among zig-zag surfaces 103. A threaded shaft 104 is secured at one end to table 101 and connects near the other end with collars 105 to prevent lateral movement thereof and a handle 106, the collars being secured to a carriage frame 107. A similar threaded shaft 108 is secured at one end to table 102 and connects at the other end with collars 109 to prevent lateral movement thereof and a handle 110, the collars being being secured to a carriage frame 111. In the construction shown, the shafts are at right angles to one another and the carriages are therefore adapted to be moved in right angle relationship to one another.

The apparatus may be operated as follows to saw oscillator blanks:

Crystal 30 is mounted on the holder with its optical axis fixed in predetermined relationship with a given or reference part of the holder, which in the apparatus shown is the inverted guide channel 31 in fixed base A. The optical axis may, for example, be determined and fixed in the manner disclosed in the copending application of Harry Berman, Serial No. 511,199, filed November 20, 1943. It is advantageously placed in parallel relationship with the guide channel, for example, the sides thereof. The electrical axis of the crystal is also fixed in predetermined relationship with a given or reference part of the

holder, which in the apparatus shown is also guide channel 31. The electrical axis may, for example, be determined and fixed in the manner disclosed in the copending application of Harry Berman, Serial No. 511,201, filed November 20, 1943. In practice it is advantageous to place the electrical axis perpendicular to the top of the guide channel.

The holder is secured to the sawing apparatus by fitting guide channel 31 in base A over adjustable guide support 12. In other words, the guide support will then fit in the guide channel fairly snugly so that the two may function in effect as a reference line or part for the cutting operation. Bolts 92 and 93 in slots 44 and 45 of base A are then tightened so that the holder is rigidly secured to the guide support. In the present construction the guide support is disposed horizontally. This leaves the optical axis of the crystal in horizontal relationship and the electrical axis in vertical relationship thereto. Saw 16 is placed in perpendicular relationship to the guide support and therefore also guide channel 31.

Since the optical and electrical axes of the crystal and the line of cut of the saw are placed in this predetermined relationship, any desired angle of cut may be obtained by swiveling adjustable guide support 12. This is accomplished by loosening set screw 97 and suitably swiveling the holder and outer hollow shaft 94 about fixed solid shaft 93 until the predetermined angle of cut 112 is obtained. This is visually indicated on scale 100. Set screw 97 is then tightened to fix the parts in their adjusted position.

With the optical and electrical axes of the crystal fixed in predetermined relationship with saw 16; the crystal may be moved to a suitable position under the saw by suitably turning handle 106 of carriage 13 and handle 110 of carriage 14. Pull-down arm 18 is then lowered to bring the saw in contact with the crystal. Power is applied to belts 25 and 28, and the saw rotates about its shaft 17. One blank after another may then be cut from the crystal, the thickness of the blanks being regulated by the amount carriages 13 and 14 are moved by handles 106 and 110. It will be clear that the reference line or part may be varied. For example, the varicus elements going into the apparatus may be so constructed that an edge or a face or even a line, as shown, through the center of the top of adjustable guide support 12, etc., or an edge or a face of guide channel 23, etc., may be employed. The important thing is to select a suitable reference line or part and then to operate the apparatus with respect to that reference line or part in order to obtain the advantages of the invention.

I claim:

1. In apparatus for manufacturing quartz oscillator plates, the improvement comprising a cutter, a guide support, a removable quartz crystal holder adapted to engage the guide support in a predetermined position; said holder comprising a fixed base, a lower tiltable base pivotally supported by the fixed base, an upper tiltable base pivotally supported by the lower tiltable base, and a rotatable base supported by the upper tiltable base, the tiltable bases being tiltable with respect to each other and the fixed base; means associated with the holder for maintaining the optical and electrical axes of a quartz crystal mounted thereon in predetermined fixed relationship to a reference part of the holder, a swivelly adjustable mounting for placing the guide support and hence the holder and crystal at a predetermined angle of cut with respect to the cutter, and means for advancing the guide support, holder and crystal as a unit to the cutter at such predetermined angle of cut while maintaining the optical and electrical axes of the crystal fixed in their predetermined relationship to the reference part of the holder.

2. In apparatus for manufacturing quartz oscillator plates, the improvement comprising a cutter, a guide support, a removable quartz crystal holder adapted to engage the guide support in a predetermined position; said holder comprising a fixed base provided with at least two pivot posts, a lower tiltable base supported by said pivot posts, the lower tiltable base also being provided with at least two pivot posts; said two sets of pivot posts being aligned at right angles to each other, an upper tiltable base supported by the latter pivot posts, and a rotatable base supported by the upper tiltable base, said tiltable bases being tiltable with respect to each other and said fixed base; means associated with the holder for maintaining the optical and electrical axes of a quartz crystal mounted thereon in predetermined fixed relationship to a reference part of the holder, means for placing the guide support and hence the holder and crystal at a predetermined angle of cut with respect to the cutter, and means for advancing the guide support, holder and crystal as a unit to the cutter at such predetermined angle of cut while maintaining the optical and electrical axes of the crystal fixed in their predetermined relationship to the reference part of the holder.

3. In apparatus for manufacturing quartz oscillator plates, the improvement comprising a cutter, a guide support, a removable quartz crystal holder adapted to engage the guide support in a predetermined position; said holder comprising a fixed base, a lower tiltable base pivotally supported by the fixed base, an upper tiltable base pivotally supported by the lower tiltable base, and a rotatable base supported by the upper tiltable base, the tiltable bases being tiltable with respect to each other and the fixed base; means associated with the holder for maintaining the optical and electrical axes of a quartz crystal mounted thereon in predetermined fixed relationship to a reference part of the holder, means for placing the guide support and hence the holder and crystal at a predetermined angle of cut with respect to the cutter, said means for placing the guide support comprising a rotatable base supporting the guide support, means associated with the latter rotatable base for determining the amount of rotation thereof with respect to the cutter, and means for advancing the guide support, holder and crystal as a unit to the cutter at such predetermined angle of cut while maintaining the optical and electrical axes of the crystal fixed in their predetermined relationship to the reference part of the holder.

4. In apparatus for manufacturing quartz oscillator plates, the improvement comprising a cutter, a guide support, a removable quartz crystal holder adapted to engage the guide support in a predetermined position; said holder comprising a fixed base, a lower tiltable base pivotally supported by the fixed base, an upper tiltable base pivotally supported by the lower tiltable base, and a rotatable base supported by the upper tiltable base, the tiltable bases being tiltable with respect to each other and the fixed base; means associated with the holder for maintaining the optical and electrical axes of a quartz crystal mounted

thereon in predetermined fixed relationship to a reference part of the holder, means for placing the guide support and hence the holder and crystal at a predetermined angle of cut with respect to the cutter, and means for advancing the guide support, holder and crystal as a unit to the cutter at such predetermined angle of cut while maintaining the optical and electrical axes of the crystal fixed in their predetermined relationship to the reference part of the holder, said latter means comprising an upper carriage supporting the guide support and being movable laterally at right angles to the cutter, and a lower carriage supporting the upper carriage, the lower carriage being movable laterally in a direction generally parallel to the cutter and at right angles to the direction of travel of the upper carriage.

5. In apparatus for manufacturing quartz oscillator plates, the improvement comprising a cutter, a guide support, a removable quartz crystal holder adapted to engage the guide support in a predetermined position; said holder comprising a fixed base, a lower tiltable base pivotally supported by the fixed base, an upper tiltable base pivotally supported by the lower tiltable base, and a rotatable base supported by the upper tiltable base, the tiltable bases being tiltable with respect to each other and the fixed base; means associated with the holder for maintaining the optical and electrical axes of a quartz crystal mounted thereon in predetermined fixed relationship to a reference part of the holder, means for placing the guide support and hence the holder and crystal at a predetermined angle of cut with respect to the cutter, said means for placing the guide support comprising a rotatable base supporting the guide support, means associated with the latter rotatable base for determining the amount of rotation thereof with respect to the cutter, and means for advancing the guide support, holder and crystal as a unit to the cutter at such predetermined angle of cut while maintaining the optical and electrical axes of the crystal fixed in their predetermined relationship to the reference part of the holder, said latter means comprising an upper carriage supporting the guide support and being movable laterally at right angles to the cutter, and a lower carriage supporting the upper carriage, the lower carriage being movable laterally in a direction generally parallel to the cutter and at right angles to the direction of travel of the upper carriage.

6. In apparatus for manufacturing quartz oscillator plates, the improvement comprising a cutter, an adjustable guide support, a removable quartz crystal holder adapted to engage the guide support in a predetermined position; said holder comprising a fixed base, a lower tiltable base pivotally supported by the fixed base, the lower tiltable base being tiltable with respect to the fixed base about a straight line axis at a fixed distance from the fixed base, means connecting the fixed base and the lower tiltable base for locking the two bases when the lower tiltable base is adjusted to a desired position, an upper tiltable base pivotally supported by the lower tiltable base, the upper tiltable base being tiltable with respect to the lower tiltable base and the fixed base about a straight line axis in angular relationship to the other straight line axis and a fixed distance from the lower tiltable base, means connecting the lower tiltable base and the upper tiltable base for locking the two tiltable bases when the upper tiltable base is adjusted to a desired position, a rotatable base supported by the upper tiltable base, and means connecting the upper tiltable base and the rotatable base for locking the two bases when the rotatable base is adjusted to a desired position; means for placing the guide support and hence the holder and crystal at a predetermined angle of cut with respect to the cutter, and means for bringing the guide support, holder and crystal as a unit and the cutter into cutting position at such predetermined angle of cut.

7. In apparatus for manufacturing quartz oscillator plates, the improvement comprising a cutter, an adjustable guide support, a removable quartz crystal holder adapted to engage the guide support in a predetermined position; said holder comprising a fixed base, a lower tiltable base pivotally supported by the fixed base, the lower tiltable base being tiltable with respect to the fixed base about a straight line axis at a fixed distance from the fixed base, means connecting the fixed base and the lower tiltable base for locking the two bases when the lower tiltable base is adjusted to a desired position, an upper tiltable base pivotally supported by the lower tiltable base, the upper tiltable base being tiltable with respect to the lower tiltable base and the fixed base about a straight line axis in perpendicular relationship to the other straight line axis and a fixed distance from the lower tiltable base, means connecting the lower tiltable base and the upper tiltable base for locking the two bases when the upper tiltable base is adjusted to a desired position, a rotatable base supported by the upper tiltable base, and means connecting the upper tiltable base and the rotatable base for locking the two bases when the rotatable base is adjusted to a desired position; a swivelly adjustable mounting for placing the guide support and hence the holder and crystal at a predetermined angle of cut with respect to the cutter, and means for advancing the guide support, holder and crystal as a unit to the cutter at such predetermined angle of cut.

8. In apparatus for manufacturing quartz oscillator plates, the improvement comprising a cutter, an adjustable guide support, a removable quartz crystal holder adapted to engage the guide support in a predetermined position; said holder comprising a fixed base, a lower tiltable base pivotally supported by the fixed base, the lower tiltable base being tiltable with respect to the fixed base about a straight line axis at a fixed distance from the fixed base, means connecting the fixed base and the lower tiltable base for locking the two bases when the lower tiltable base is adjusted to a desired position, an upper tiltable base pivotally supported by the lower tiltable base, the upper tiltable base being tiltable with respect to the lower tiltable base and the fixed base about a straight line axis in perpendicular relationship to the other straight line axis and a fixed distance from the lower tiltable base, means connecting the lower tiltable base and the upper tiltable base for locking the two bases when the upper tiltable base is adjusted to a desired position, a rotatable base supported by the upper tiltable base, and means connecting the upper tiltable base and the rotatable base for locking the two bases when the rotatable base is adjusted to a desired position; a swivelly adjustable mounting for placing the guide support and hence the holder and crystal at a predetermined angle of cut with respect to the cutter, and means for advancing the guide support, holder and crystal as a unit to the cutter at such predetermined angle of cut.

9. In apparatus for manufacturing quartz oscillator plates, the improvement comprising a cutter, an adjustable guide support, a removable quartz crystal holder adapted to engage the guide support in a predetermined position; said holder comprising a fixed base, a lower tiltable base pivotally supported by the fixed base, the lower tiltable base being tiltable with respect to the fixed base about a straight line axis at a fixed distance from the fixed base, means connecting the fixed base and the lower tiltable base for locking the two bases when the lower tiltable base is adjusted to a desired position, an upper tiltable base pivotally supported by the lower tiltable base, the upper tiltable base being tiltable with respect to the lower tiltable base and the fixed base about a straight line axis in angular relationship to the other straight line axis and a fixed distance from the lower tiltable base, means connecting the lower tiltable base and the upper tiltable base for locking the two tiltable bases when the upper tiltable base is adjusted to a desired position, a rotatable base supported by the upper tiltable base, and means connecting the upper tiltable base and the rotatable base for locking the two bases when the rotatable base is adjusted to a desired position; means for placing the guide support and hence the holder and crystal at a predetermined angle of cut with respect to the cutter, and means for bringing the guide support, holder and crystal as a unit and the cutter into cutting position at such predetermined angle of cut.

10. In apparatus for manufacturing quartz os-

cillator plates, the improvement comprising a cutter, an adjustable guide support, a removable quartz crystal holder adapted to engage the guide support in a predetermined position; said holder comprising a fixed base, a lower tilttable base pivotally supported by the fixed base, the lower tilttable base being tilttable with respect to the fixed base about a straight line axis at a fixed distance from the fixed base, means connecting the fixed base and the lower tilttable base for locking the two bases when the lower tilttable base is adjusted to a desired position, an upper tilttable base pivotally supported by the lower tilttable base, the upper tilttable base being tilttable with respect to the lower tilttable base and the fixed base about a straight line axis in perpendicular relationship to the other straight line axis and a fixed distance from the lower tilttable base, means connecting the lower tilttable base and the upper tilttable base for locking the two bases when the upper tilttable base is adjusted to a desired position, a rotatable base supported by the upper tilttable base, and means connecting the upper tilttable base and the rotatable base for locking the two bases when the rotatable base is adjusted to a desired position; means for placing the guide support and hence the holder and crystal at a predetermined angle of cut with respect to the cutter, and means for bringing the guide support, holder and crystal as a unit and the cutter into cutting position at such predetermined angle of cut.

10. In apparatus for manufacturing quartz oscillator plates, the improvement comprising a cutter, an adjustable guide support, a removable quartz crystal holder adapted to engage the guide support in a predetermined position; said holder comprising a fixed base, a lower tilttable base pivotally supported on pivoting means secured to the fixed base, the lower tilttable base being tilttable with respect to the fixed base about a straight line axis at a fixed distance from the fixed base, means connecting the fixed base and the lower tilttable base for locking the two bases when the lower tilttable base is adjusted to a desired position, an upper tilttable base pivotally supported on pivoting means secured to the lower tilttable base, the upper tilttable base being tilttable with respect to the lower tilttable base and the fixed base about a straight line axis in perpendicular relationship to the other straight line axis and a fixed distance 35 40 45 50

from the lower tilttable base, means connecting the lower tilttable base and the upper tilttable base for locking the two bases when the upper tilttable base is adjusted to a desired position, a rotatable base supported by the upper tilttable base, and means connecting the upper tilttable base and the rotatable base for locking the two bases when the rotatable base is adjusted to a desired position; means for placing the guide support and hence the holder and crystal at a predetermined angle of cut with respect to the cutter, and means for advancing the guide support, holder and crystal as a unit to the cutter at such predetermined angle of cut.

5 11. In apparatus for manufacturing quartz oscillator plates, the improvement comprising a cutter, an adjustable guide support, a removable quartz crystal holder adapted to engage the guide support in a predetermined position; said holder
0 comprising a fixed base, a lower tiltable base pivotally supported on pivoting means secured to the fixed base, the lower tiltable base being tiltable with respect to the fixed base about a straight line axis at a fixed distance from the fixed base,
5 means connecting the fixed base and the lower tiltable base for locking the two bases when the lower tiltable base is adjusted to a desired position, an upper tiltable base pivotally supported on pivoting means secured to the lower tiltable base,
0 the upper tiltable base being tiltable with respect to the lower tiltable base and the fixed base about a straight line axis in perpendicular relationship to the other straight line axis and a fixed distance from the lower tiltable base, means connecting the lower tiltable base and the upper tiltable base for locking the two bases when the upper tiltable base is adjusted to a desired position, a rotatable base supported by the upper tiltable base, and means connecting the upper
5 tiltable base and the rotatable base for locking the two bases when the rotatable base is adjusted to a desired position; means for placing the guide support and hence the holder and crystal at a predetermined angle of cut with respect to the cutter, and means for bringing the guide support, holder and crystal as a unit and the cutter into cutting position at such predetermined angle of cut.
